UNITED STATES PATENT OFFICE.

ERWIN LAVENS AND EDWARD JOSEPH LAVENS, OF BROOKLYN, NEW YORK.

SIGNAL-TELEGRAPH.

SPECIFICATION forming part of Letters Patent No. 695,568, dated March 18, 1902.

Application filed January 7, 1901. Serial No. 42,448. (No model.)

To all whom it may concern:

Be it known that we, ERWIN LAVENS and EDWARD JOSEPH LAVENS, citizens of the United States, residing at the borough of Brooklyn, city of New York, county of Kings, State of New York, have invented certain new and useful Improvements in Signal-Telegraphs, of which the following is a specification.

10 Our improved signal-telegraph consists, essentially, of an order-transmitting instrument, an order-receiving instrument, and an electromagnetic circuit-controlling device interposed in suitable circuits between the two, 15 the object of the invention and arrangement of parts being, first, for the purpose of permitting an officer to send an order—for instance, to the engine-room of a vessel—and be informed by his own act that his order has 20 been received, and, secund, by the act of the engineer in the engine-room that such order has been executed, and, further, by the special arrangement of parts insure that in case 25 one portion of the indicating apparatus should be disabled for any cause a second portion would be operative, or in case both of such portions are disabled that the signal apparatus so far as relates to the transmission of orders and considered apart from the indicating 30 apparatus will still be effective.

The accompanying drawings will serve to illustrate our invention.

Figure 1 is a diagrammatic view showing a transmitting instrument and a receiving instrument in circuit with the accompanying parts, both instruments shown as front elevations with a portion of their interior mechanism in dotted lines. Fig. 1^a is a diagrammatic view corresponding to Fig. 1 and showing the circuit connections between the different parts. Fig. 2 is a front elevation of the transmitting instrument with the front dial removed. Fig. 3 is a vertical section through the transmitting instrument. Fig. 4 is a front elevation of the receiving instrument with a portion of the cover broken away. Fig. 5 is a vertical section through the receiving instrument on the line X X of Fig. 4. Fig. 6 is a plan view of one magnet, lamp, and shutter of the receiving instrument as shown in Fig. 5.

Similar numerals and letters indicate like parts.

In the drawings, A indicates the transmitting instrument; B, receiving instrument; C, 55 dynamo-electric machine or other source of electrical energy; D, electromagnetic circuit-controlling device interposed between the transmitting and receiving instruments and preferably located in the engine-room; E, engine-room switch under the control of the engineer; F, electric bells.

The transmitting instrument consists of an inclosing casing 10, which may be of wood, rubber, or other similar material and provided with an order-transmitting handle 11, 65 mounted on a shaft 12, carried in the hub-bearing 13, secured to or forming a part of the casing 10. The front of the casing is closed by a glass plate or dial 14, painted or 70 otherwise colored upon its interior, excepting where the words indicating signal-orders appear—as, for instance, as is shown in Fig. 1, where at the right-hand side of the plate or dial appear the words "Ahead," "Slow," 75 "Half," "Full;" at the center, "Stop;" at the left, "Astern," "Slow," "Half," "Full." Any other system of signal-orders may be employed. The glass plate or dial 14 is held in position by means of a suitable securing-ring 15.

Located equidistant around the top of the casing 10 and corresponding in position with the signal-orders on the face of the instrument are V-shaped slots 16, and coöperating 85 with these slots is a plunger 17, with a V-shaped point. The top of the plunger is connected to a lever 18, pivoted in the handle 11. Arranged under the upper arm of the lever 18 is a spring 19, which serves to force the lever outward and push the end of the plunger 17 downward into the slot 16. Connected to the handle and projecting downward over the face of the plate or dial 14 is a pointer 20. Situated within the casing and secured by 90 means of studs 21 is a plate of insulating material 22, on which is mounted a series of contacts—to wit, first, a series of six separated plates H, arranged equidistant, over the upper half of the face of the instrument and 95 electrically connected by means of a plate 23 on the back of the insulating-plate 22, the

plates H being located midway between the slots 16 on the outer surface of the case of the instrument; second, a series of seven separated contact-buttons I to I⁶, inclusive, insulated from each other; third, a series of seven separated contact-buttons J to J⁶, inclusive, electrically connected through a plate 24 on the back of the insulating-plate 22, the contact-buttons I to I⁶ and J to J⁶ being located in pairs in positions corresponding to the positions of the slots 16; fourth, an annular contact-ring K, located at about the center of the insulating-plate 22. At the bottom of the insulating-plate 22 are a series of ten terminals 25, through which the transmitting instrument is connected in circuit with a source of electrical energy, the electromagnet device D, and the receiving instrument.

Mounted upon the shaft 12 and rotating with it is an arm 26, carrying spring-pressed contact-pins L M N O. These pins are insulated from the arm and from each other by means of the bushings 27.

Arranged within the handle is a switch P, which is normally closed.

Mounted on a suitable standard in the interior of the casing and immediately back of the glass plate or dial 14 are two electric lamps G' G², preferably of different colors.

The receiving instrument B consists of an inclosing casing 30, provided with a glass plate or dial 31, painted or otherwise colored upon its interior, except over the circular portions 32 33. The portions marked 32 we prefer to give a color contrasting to that of the body of the plate. For instance, if the body of the plate is black the portions 32 would be colored red or blue. The portions marked 33 are preferably left clear and transparent.

The number of pairs of circular portions 32 33 on the front of the receiving instrument conform to the system of signal-orders on the transmitting instrument, and the dial of the receiving instrument is correspondingly lettered with signal-orders from left to right. Both transmitting and receiving instruments are marked with seven orders. The number of orders may be increased or diminished.

Mounted upon a suitable standard in the interior of the receiving instrument and immediately back of the circular portions 32 are the lamps G and magnets R. Situated under each magnet R, Fig. 5, is an armature 34, secured to an arm 35, pivoted to the magnet-supporting frame at 36. On the forward end of the arm 35 are mounted insulated contact-pins 37 38. Projecting transversely from the armature are the pivot-pins 39, which are carried through two arms of a lever carrying on its forward end a shutter 40, located behind one of the clear circular portions 33 and pivoted at its rear end at 41 to the magnet-supporting frame. Located under the contact-pins 37 38 are the contact-plates 42 43, and at opposite sides of this pair of contact-plates are the terminal plates 44 45. It will be observed on reference to Fig. 4 that there

are two contact-plates and two terminal plates for each magnet.

The electromagnetic device D, which is used for closing a preliminary circuit between the receiving instrument and the transmitting instrument, consists of an ordinary magnet, under which is located a pivoted armature 46, on the end of which is mounted the contact-pins 47 48. The construction of the device is such that when the magnet is energized the contact-pins 47 48 move downward and make contact with contact-plates 49 50 arranged under them.

a' a² a³ a⁴ a⁵ a⁶ a⁷ indicate conductors, each connected at one terminal to the series of contact-terminals 45 at the receiving instrument and at their opposite terminals to the series of contact-buttons I I' I² I³ I⁴ I⁵ I⁶ at the transmitting instrument; b, a conductor connecting all the series of contact-terminals 44 at the receiving instrument; c, a conductor connecting all the series of contact-plates 42; d, a conductor connecting all the series of contact-plates 43; b', a conductor connecting conductor b and the contact-terminals 44 with the contact-pin 47 at the electromagnetic device; c', a conductor connecting conductor c and contact-plates 42 with one terminal of the lamp G' at the transmitting instrument; d', a conductor connecting the conductor d and contact-plates 43 with one terminal of the lamp G² at the transmitting instrument; e, conductor connecting one terminal of the magnet D of the electromagnetic device with the series of contact-plates H at the transmitting instrument; f, a conductor connected at one terminal to the conductor b', passing through the bells F and connected at its opposite terminal to the contact-plate 50 of the electromagnetic device and also connected through conductor f' with the contact-ring K at the transmitting instrument; e', a conductor connected at one terminal with the magnet D and at the other terminal to one contact of the engineer's switch E; e², a conductor connected at one terminal to the contact-plate 49 of the electromagnetic device and at its opposite end to one contact of the engineer's switch E; e³, a conductor connecting conductor e² with one brush of the dynamo-electric machine C; g, a conductor connected to one terminal of each of the lamps G' G² and to contact-button J³ of the transmitting instrument; h, conductor leading from terminal plate 45 to one terminal of magnet R; i, conductor leading from the opposite terminal of magnet R to terminal plate 44; j, conductor leading from conductor i to one terminal of the lamp G, thence through lamp to contact-pin 37; k, conductor leading from contact-pin 38 to conductor h.

It will be seen from the description and drawings that the lamps G at the receiving-station are arranged to be individually coupled in series with the lamp G' at the transmitting-station and that the magnets R at the receiving-station are arranged to be individually coupled in series with the lamp G² at

the transmitting-station, and also that the magnets R at the receiving-station are arranged to be individually coupled in a separate circuit from those including the lamps 5 at the transmitting-station, and, further, that these three circuits are in parallel.

The operation of our improved device may be described as follows: Assuming the handle to be in the position shown in the drawings—*i. e.*, with the pointer over “Stop”—with the handle in this position—*i. e.*, at rest over one of the slots 16—the plunger 17 engages in the slot and the switch P is closed. Contacts 37 42 38 43 at the receiving instrument and 47 49 48 50 at the electromagnetic device are separated and all circuits from the source of energy open. If, now, it is desired to transmit the order “slow astern,” the handle 11 is moved to the left. This movement 20 of the handle to the left brings contact-pin L in contact with plate H, thereby establishing a circuit to energize the magnet D of the electromagnetic device, said circuit being as follows: from plate H by conductor e to magnet D, by conductor e' to engineer's switch E, by conductors e²e³ to dynamo C, from dynamo by conductors f f' to contact-ring K, to contact-pin N, by conductor l to contact-pin L. The effect of closing the circuit described 25 30 through the magnet D of the electromagnetic device is to bring the insulated contact-pins 47 48, respectively, in contact with the contact-plates 49 50, thereby establishing two circuits, one to the bells, by reason of which the fact is audibly indicated at the transmitting 35 and receiving stations that the line is in order, and one to maintain the activity of the magnet D after the first circuit, as described, between the transmitting instrument and the 40 magnet D is broken by the further movement of the handle to the left. The circuit through the bells is as follows: from dynamo C by conductor f to bells F, by conductor b', contact-pin 47, contact-plate 49, by conductors e² 45 e³ back to dynamo. The circuit to maintain the magnet D is as follows: from dynamo C by conductor f to contact-plate 50, contact-pin 48, by conductor e⁴ to magnet D, by conductor e' to engineer's switch E, by conductor 50 e²e³ back to dynamo. Further movement of the handle to the left causes the contact-pin L to leave the contact-plate H. This breaks the first circuit established through the magnet D. The magnet D, however, is 55 maintained active by reason of the circuit including the magnet and the source of energy, as described. As the movement of the handle is continued to the left the contact-pin M is brought in contact with the contact-button I², and at this point the plunger 17 in the handle is allowed to drop in the slot 16. This establishes a circuit to the receiving instrument as follows: The circuit to the receiving instrument is from dynamo C by conductors 60 f f', contact-ring K, contact-pin N, conductor m, included in the handle 11 of the transmitting instrument, to one terminal of the switch 65

P, thence to contact-pin M, to contact-button I², conductor a³, to terminal plate 45 at the receiving instrument, thence through conductor 70 h, magnet R, conductor i, terminal plate 44, conductor b', to contact-pin 47, contact-plate 49, conductors e²e³ to dynamo, which completes the circuit. The closure of the second-described circuit through the magnet R 75 causes the magnet to actuate its armature 34, which elevates a shutter 40 in front of one of the disk portions 33, as indicated at the central disk, Fig. 1, depresses the forward end of the arm 35, and closes the contacts 37 42 80 38 43. The effect of closing these contacts is to establish two circuits, as follows: First circuit: from dynamo C to conductors f f', contact-ring K, contact-pin N, conductor n, contact-pin O, button J¹, conductor g, lamp G', conductor c', contact-plate 42, contact-pin 37, to lamp G, from lamp G, through conductor j, to conductor i, to terminal plate 44, conductor b', contact 47, contact 49, conductors e²e³, to dynamo. Second circuit: from 85 dynamo C, conductors f f', contact-ring K, contact-pin N, conductor n, contact-pin O, button J¹, conductor g, through lamp G², conductor d', contact-plate 43, contact-pin 38, conductors k h, magnet R, conductor i, terminal plate 44, conductor b', contact 47, contact 49, conductors e²e³, to dynamo. After an order has been transmitted a light and a shutter at the receiving-station, two lights at the transmitting-station, and the bells at 90 both stations, assuming all circuits to be in order, will be maintained in operation until such time as the engineer gives notice that the order transmitted has been obeyed. This is accomplished on his part by merely opening 95 the normally-closed switch E, which breaks all circuits and allows all parts, with the exception of the handle and switch-arm at the transmitting instrument, to return to their original position and condition. At 100 such time the officer at the transmitting-station can or not, as he sees fit, move the handle back to the stop position. Signal orders may be given from any position of the handle.

It will be understood that as the circuits 105 which include the magnet R or which include the lamps G G' or which include the magnet R and lamp G² are in parallel that either or both of the last two mentioned circuits may be interrupted without in anywise interfering with the transmission of a signal. If the circuit including the lamps G G' is interrupted, the circuits including the magnet R and the lamp G², as well as the circuit including the magnet R, will remain effective, or if both 110 lamp-circuits are broken the circuit including the magnet R will still remain effective. In the latter case, however, the officer on the bridge will have no visible means of knowing so far as the transmission apparatus is 115 concerned whether or not the signal transmitted has or not been observed, but will be informed by the bell at the transmitting instrument ceasing to ring when the engineer's 120 125 130

switch has been opened. It will further be understood that no order will be given upon moving the handle to the right or left over the transmitting instrument unless the pin 5 17 is dropped into one of the slots 16 and the switch in the handle permitted to close. This enables the operator to pass over any intermediate point in the instrument, as in passing from "stop" to "full ahead" or "full 10 astern."

Having thus described our invention, we claim—

1. In a signal-telegraph, a transmitting instrument comprising an inclosing casing having a series of slots upon its periphery, a disk 15 of insulating material mounted upon the interior of the casing provided with a series of connected plates interposed in position between said slots, two series of contact-buttons 20 which correspond in position with said slots, a contact-ring, an oscillating handle provided with an arm carrying contact-pins which contact with said contacts, and a plunger which coacts with said slots.

25 2. In a signal-telegraph, a transmitting instrument embodying a casing, a series of slots on the periphery of the casing, an oscillating handle, a lever, a plunger controlled by said lever mounted in said handle and co-operating with said slots, and a normally-closed switch in the handle adapted to be opened by the lever when employed to lift the plunger.

3. In a signal-telegraph, the combination of a transmitting instrument, a receiving instrument, an independent electromagnetic circuit-controlling device interposed between the two, means energized by the transmitting instrument to close a circuit through the controlling device, and means actuated by the 35 controlling device to close a series of circuits between the transmitting and receiving instruments.

4. In a signal-telegraph, the combination of a transmitting instrument, a receiving instrument, an electromagnetic circuit-controlling device between the two, means energized by the transmitting instrument to close the circuit through the controlling device, means actuated by the controlling device to close a 45 series of circuits between the transmitting and receiving instruments, and means under the control of the operator of the receiving instrument for breaking the circuit between the transmitting instrument and controlling device.

5. In a signal-telegraph, the combination of a transmitting instrument provided with two lamps, a receiving instrument provided with a series of lamps individually in series

60 with one of said lamps, and a series of magnets individually in series with the other of said lamps; and a controlling device interposed between said transmitting and receiving instruments, energized by the action of the transmitting instrument and which will 65 act to close circuits between said lamps and magnets.

6. In a signal-telegraph, the combination of a transmitting instrument provided with two lamps, a receiving instrument provided 70 with a series of lamps and a series of magnets, independently in series relation and in circuit with the separate lamps at the transmitting instrument, a series of magnets at the receiving instrument in series and circuit 75 relation with the transmitting instrument, and a controlling device energized by the transmitting instrument for closing said circuits through said parts.

7. In a signal-telegraph, the combination 80 of a transmitting instrument, a receiving instrument, a circuit-controlling device, a circuit between said transmitting instrument and controlling device, and three circuits under the control of the controlling device containing respectively a lamp at the transmitting instrument, and a lamp at the receiving instrument; a lamp at the transmitting instrument and a magnet at the receiving instrument; the transmitting instrument and 85 a magnet at the receiving instrument.

8. In a signal-telegraph, the combination of a transmitting instrument, a receiving instrument, a device for making audible signals, and a circuit-controlling device energized from the transmitting instrument and adapted to close three circuits; one through the audible signals, one to the receiving instrument; one to maintain the circuit connections through its magnet.

9. In a signal-telegraph, the combination of a transmitting instrument, a receiving instrument, a circuit-controlling device energized by the transmitting instrument, an independent circuit including bells at the receiving and transmitting stations and under the control of the controlling device, and circuits including lamps and magnets at the transmitting and receiving instruments also under the control of the controlling device.

105 In testimony whereof we affix our signatures in the presence of two witnesses.
